UNITED STATES PATENT OFFICE.

CHARLES EMILE PIGACHE AND PIERRE PIGACHE, OF PARIS, FRANCE.

LOCKING DEVICE FOR DERAILED TROLLEY-ARMS.

1,339,221.

Specification of Letters Patent.

Patented May 4, 1920.

Application filed May 18, 1917. Serial No. 169,594.

To all whom it may concern:

Be it known that we, CHARLES EMILE PIGACHE and PIERRE PIGACHE, engineers, two citizens of the Republic of France, residents of Paris, (post-office address 206 Rue de Charenton,) France, have invented a new and useful Locking Device for Derailed Trolley-Arms, which locking device is fully set forth in the following specification.

10 The present invention relates to a device for momentarily stopping, or at least retarding, the upward movement of a derailed trolley pole, and it proposes an improved device of this nature which is applicable either to 15 a trolley pole mechanism of the ordinary type, or to a pole equipped with an automatic releasing and folding mechanism of the character shown and described in our prior Patent, No. 1,187,782, issued June 20, 1916.

The invention also resides in the provision of a device of the kind above specified which may be applied to a trolley pole equipped with an alining mechanism such as shown 25 and described in our later Patent, No. 1,219,769, issued March 20, 1917, without interfering in any way with the automatic operation of said mechanism.

The accompanying drawing shows, in a somewhat diagrammatic manner, various forms of locking devices constructed in accordance with the invention and applied to trolley pole mechanisms of different characters.

35 In said drawing:

Figures 1, 2 and 3 represent the invention applied to a trolley pole mechanism of the type disclosed in the earlier of our two prior 40 patents above identified, and show the positions which the various parts assume during successive stages in the operation;

Fig. 4 shows a slightly modified form of locking device applied to a mechanism of the same type; said mechanism being additionally equipped with an alining device of the character disclosed in the other of our two 45 said patents;

Fig. 5 shows a further modified form of locking device; and

50 Fig. 6 shows the invention, in a still further modified form, applied to a trolley pole of the ordinary type.

Referring to Figs. 1, 2 and 3, 1 indicates

the trolley pole proper, which may be of the usual or any preferred construction, 2 the 55 socket wherein it is fitted, and 3 the rotatable sleeve to which said socket is connected and which is itself mounted on a suitable base 4, these parts being shown in dotted lines. The connections 6 between the socket 2 and sleeve 60 3 which control the automatic release and folding of the pole may be, and preferably are of the character illustrated diagrammatically in Fig. 1 of our said Patent No. 1,187,782, and are fully described therein. 65 They form in themselves no part of the present invention, and for that reason they need not be explained herein and are merely indicated in dotted lines.

The locking device, in which the invention resides, is represented in said figures as in the form of a cam plate 12 having somewhat the shape of a sector, said plate being pivoted at its apex on a lateral stud or pin 13, which is likewise fastened to the sleeve 75 3. This plate 12 is provided adjacent its apex with a shoulder 14 for co-action with the terminal nose 11 of an arm 10, as hereinafter explained, said arm forming an extension of a link 5 which is attached at its 80 upper end to a pin 7 fixed to the socket and has a pivotal mounting at its lower end on a pin 8 carried by the end of a bracket 9 which is fastened to the sleeve 3. The peripheral edge of said plate may be provided 85 with teeth 15 for engagement with a pin or stud 16, that projects laterally from the pole socket 2, though the teeth may be omitted, if desired, and the edge of the plate left plain, as is the case with the cam 12' in 90 Fig. 4.

Fig. 1 shows the normal position of the several parts, the nose 11 of the arm 10 bearing against the shoulder 14 on the cam 12 and thereby holding said cam above and out of engagement with the pin 16. When the pole is suddenly forced downward from any cause, its wheel or head leaves the wire, as will be understood, and immediately thereafter the pole tends, under ordinary conditions, to swing abruptly upward. During this initial movement of the pole, the connecting arm 5, 10 is caused to swing or rock toward the left, as indicated by the arrow *a* in Fig. 1, which frees the nose 11 from shoulder 14 and thereby permits the cam 12

to drop by gravity. The peripheral edge of said plate is eccentric to the pivot 13 and is so disposed with relation to the stud 16 that as the plate swings down, its edge gradually 5 approaches, and ultimately binds against said stud, as will be apparent from Figs. 2 and 3, the latter figure showing the parts in locked position. The parts assume their original positions during the reengagement 10 of the pole head or wheel with the wire, which takes place in the manner described in our said Patent, No. 1,187,782, the arm 5, 10 moving toward the right at such time, and the nose 11 of said arm engaging and lifting 15 the cam 12 until the pole head again contacts with the wire.

The construction represented in Fig. 4 operates in the same general manner as that just described, but includes an additional 20 device in the nature of an aliner, generally indicated at 17, which acts to automatically bring back the pole, after it has jumped the wire, to a position within the limits of the car area; said device forming the subject 25 of our said prior Patent No. 1,219,769, to which reference may be had for a complete description. In the form of the invention represented in Fig. 4, the locking plate or cam 12' is pivoted on the stud or pin 16' on 30 the pole socket 2, and is provided with a pin or lug 18, which projects through a longitudinal slot 19 formed in a bar 20. The latter is pivoted at its rear end to the extension 10' of the link 5', said extension being elongated and curved at its free end, as indicated at 11'. The peripheral edge of the cam is designed to coact with the pin or stud 13' on the sleeve 3, but is normally held away from said stud by the bar slot 19, the 35 inner end wall of which supports the cam in raised position. When disengagement of the pole takes place, the connecting arm 5', 10' swings to the left as before, with the result that the slotted bar 20 is pulled endwise in the same direction. This movement 40 of the bar releases the locking cam 12', due to the travel of pin 18 in slot 19, said cam swinging downward and ultimately binding against the stud 13'. The return of the 45 parts to their respective normal positions is effected by the reengagement of the pole with the wire.

In the modified construction shown in Fig. 5, the locking member 12' is controlled 50 by a bar 18' having a slot-and-pin connection 19', 20' with said member, the bar being pivoted at its lower end at 7' to the connecting device 6'. The arrangement is such that the locking member or cam, which is 55 preferably wedge-shaped, is normally held in raised or inactive position, but is released by the downward movement of its controlling bar, produced consequent upon the disengagement of the pole. The cam then

drops into binding engagement with the pin 65 or stud 16' on the pole socket.

The several constructions above described show the locking cams as operating by gravity when released, but it will be obvious that they can be positively operated by means of 70 springs, weights or the like, if desired, illustration thereof being considered unnecessary since the action is in no way changed.

Fig. 6 shows the invention applied to an ordinary trolley pole 1^a, which is fitted in 75 a socket 2^a pivoted at 7^a to the pole support 3^a. The locking member or cam 12^a is pivoted on a pin or stud 13^a, fixed to the support 3^a, and co-acts with a controlling member 21, in the form of a lever which 80 is centrally fulcrumed on the pivot pin 7^a and is provided at opposite sides of said pivot with a pair of curved stops or lugs 22 and 23. The upper arm of said lever has an extension or finger 24, which projects 85 upwardly at right angles thereto and is designed to co-act with a stud or pin 25 on the cam 12^a. This pin 25 is fixed to a projection or nose 26 on the periphery of the cam, and is engageable in a notch 27 formed 90 in the controlling lever 21 at the base of the extension 24. The said nose 26 is normally received in this notch, and its pin 25 contacts with the edge face of the lever, as clearly shown in Fig. 6. In consequence of 95 this arrangement, it will be apparent that when the pole leaves the wire and starts to move upward, its socket 2^a will press against the upper stop lug 22, with the result that the lever 21 will be rocked counter-clockwise 100 about its pivot 7^a and will thereby disengage the cam nose 26 from the notch 27. The cam will then swing downward and come into binding engagement with the socket, thus checking further upward movement of the pole; and if the latter is subsequently depressed slightly from any cause, the cam will tend to continue its downward 105 rocking movement, thus increasing its binding or wedging action. Reengagement of 110 the pole is effected by moving it downward until its socket strikes against the lower stop lug 23 on the controlling lever, whereupon the latter will be rocked in a clockwise 115 direction about pivot 7^a. During this movement, the lower edge of the extension 24 will ride along the pin 25, and will swing the cam upwardly counter-clockwise about its pivot 13^a, until at the conclusion thereof, the parts will have assumed the positions 120 represented in Fig. 6, with the nose 26 again received in notch 27 and the edge of the cam out of contact with the socket.

It is to be observed that in all of the forms of the invention, the locking member 125 or cam is under the direct and sole control of the socket, which term, as applied in the appended claims, is intended to cover the

element 2 as an entirely, *i. e.*, not only the apertured part in which the pole end actually fits, but also the portions to which the pins or studs 7 and 16 are fixed. The entire locking mechanism can thus be disposed at the base of the pole, with the result that the action is simplified as compared with constructions wherein the trolley wheel or other part at the free end of the pole is relied on to actuate the locking devices through the agency of intermediate connections.

We claim as our invention:—

1. In a trolley mechanism, the combination, with a base, a socket pivotally connected therewith, and a pole fitted in said socket; of a movable locking member associated with the socket for holding the pole against upward movement; and a device normally retaining said locking member in ineffective position, but adapted to be operated mechanically by the movement of the socket when the pole leaves the wire to automatically release the locking member and thereby permit its movement into effective position.

2. In a trolley mechanism, the combination, with a base, a socket pivotally connected therewith, and a pole fitted in said socket; of a locking cam associated with the socket for holding the pole against upward movement; and a member normally retaining said cam in ineffective position, but adapted to be operated mechanically by the movement of the socket when the pole leaves the wire to automatically release the cam and thereby permit its movement into effective position.

3. In a trolley mechanism, the combination, with a base, a socket pivotally connected therewith, and a pole fitted in said socket; of a locking member movable into binding engagement with said socket to hold the pole against upward movement; and a device under the sole control of said socket for normally retaining said member in ineffective position for such engagement, but adapted to be operated by the movement of the socket when the pole leaves the wire to automatically release said device and thereby permit it to so engage said socket.

4. In a trolley mechanism, the combination, with a base, a socket pivotally connected therewith, and a pole fitted in said socket; of a locking member for holding the pole against upward movement; a controlling member directly co-operative with said locking member for normally holding it in ineffective position but automatically releasable from it when the pole leaves the wire to permit its movement into effective position; and means under the sole control of said socket for operating said controlling member.

5. In a trolley mechanism, the combination, with a base, a socket pivotally connected therewith, and a pole fitted in said socket; of a pivotally mounted cam movable into and out of binding engagement with the socket to hold the pole against upward movement; and a device carried by said socket and movable relatively to the same normally retaining said cam in ineffective position for such engagement, but automatically releasable therefrom when the pole leaves the wire to permit it to so engage said socket.

6. In a trolley mechanism, the combination, with a base, a socket pivotally connected therewith, and a pole fitted in said socket; of a pivotally mounted locking cam movable into and out of position to hold the pole against upward movement; and a device pivoted to said socket and having a portion directly co-acting with said cam to normally retain it in ineffective position, but automatically releasable therefrom when the pole leaves the wire to permit its swinging movement into effective position.

7. In a trolley mechanism, the combination, with a base, a socket pivotally connected therewith, and a pole fitted in said socket, said base and said socket being each provided with a lateral projection; of a cam pivoted on one of said projections and adapted to swing into and out of locking engagement with the other to hold the pole against upward movement; and a device under the direct and sole control of said socket normally retaining said cam in ineffective position, for such engagement, but automatically releasable therefrom when the pole leaves the wire to permit its movement into position to so engage said projection.

8. In a trolley mechanism, the combination, with a base, a socket pivotally connected therewith and provided with a lateral projection, and a pole fitted in said socket; of a cam movable into and out of locking engagement with said projection to hold the pole against upward movement; and a device under the direct and sole control of said socket normally retaining said cam in ineffective position, for such engagement, but automatically releasable therefrom when the pole leaves the wire to permit its movement into position to so engage said projection.

9. In a trolley mechanism, the combination, with a base, a socket pivotally connected therewith, and a pole fitted in said socket, the socket and base constituting companion parts, one of which is provided with a lateral projection; of a pivoted cam adapted to swing into and out of locking engagement with said projection to hold the pole against upward movement; and a device

under the direct and sole control of said socket normally retaining said cam in ineffective position, for such engagement, but automatically releasable therefrom when the pole leaves the wire to permit its movement into position to so engage said projection.

In testimony whereof we have signed this

specification in the presence of two subscribing witnesses.
